UNITED STATES PATENT OFFICE

RALPH S. McNANEY, OF DOWAGIAC, MICHIGAN, ASSIGNOR TO DOWAGIAC STEEL FURNACE COMPANY, OF DOWAGIAC, MICHIGAN, A CORPORATION OF MICHIGAN

FURNACE

Application filed October 22, 1928. Serial No. 314,209.

The invention relates to warm air furnaces adapted for both gaseous liquid or solid fuel.

The primary object of the invention is to provide a construction which is gas-tight throughout, thereby insuring that the products of combustion are confined within the chamber and flue passageways and are not permitted to escape into the casing area or into the furnace room.

Another object is to provide a composite construction having both sheet metal and cast metal parts joined together in such a manner as to insure gas-tight joints under all conditions of operation. Another object is to construct the parts in such a manner as to render the combustion chamber and flue passageways substantially seamless.

These and other objects are attained in the improved furnace construction hereinafter more fully described and illustrated in the accompanying drawings, wherein

Figure 1 is a central longitudinal section through the improved furnace;

Figure 2 is an elevation of the furnace with the outer casing removed showing the main drum and the radiator;

Figure 3 is an axial section through the damper operating mechanism;

Figure 4 is a section on the line 4—4 of Figure 3;

Figure 5 is an enlarged view of the welded joint between the door frame and the furnace.

In the present state of the art furnaces are usually constructed either completely of cast metal parts or of the combination of cast metal and sheet metal parts. The joints between engaging parts are secured by bolts, rivets or screws or other suitable means and it is also necessary to putty or seal these joints to prevent passage therethrough of the gaseous product of combustion. It is, however, difficult to always maintain a gas-tight seal for differences in expansion of the parts will frequently open the joints. In my improved furnace construction substantially all of the adjacent sections are secured together by welding, thereby permanently integrating the same. The furnace is constructed of both sheet metal and cast metal parts, the latter be-

ing used where it is particularly desirable, either because of the requirement for rigidity or because the design of the parts is more readily obtained by the use of cast rather than sheet metal. Where the cast metal parts are joined to the sheet metal parts I have provided such materials as can be permanently welded together in order to maintain tight joints, and I have therefore used materials having substantially the same coefficient of expansion. More specifically, I have provided a construction using sheet steel and cast steel since these two materials have substantially the same coefficient of expansion and can be welded together to form an integral structure having a gas-tight joint. The use of cast steel for the casting sections adjacent the sheet metal sections instead of the use of the more common material, cast iron, makes a far better construction for it eliminates the necessity of calking the joints between the cast and sheet metal parts with putty or other equivalent substances and it eliminates the use of bolts, rivets, screws and the like and also eliminates joints between materials of unequal coefficient of expansion and substitutes for the above a strong, durable leak-proof and substantially seamless housing for the combustion gases.

In detail, 10 is a cylindrical drum preferably formed of heavy sheet steel and having at its upper end a dome-shaped head 11 with a flange 12 telescopically engaging the drum. Head 11 is electrically welded to the top end of drum 10 at the shoulder of flange 12 as indicated at 13 and there is also another weld 14 between the lower end of flange 12 and the inside portion of drum 10, thus making a double welded joint for the full circumferential distance between drum 10 and head 11. 15 is a fire door extension of the drum 10 which also is preferably formed of sheet steel having its inner end welded at 16 to the drum. At the outer end of this extension 15 is a cast steel door frame 17 having a flange 18 overlapping the member 15 and with its end welded to said member as indicated at 19. Thus, the cast metal door frame 17 is united to the sheet metal extension of the drum in a permanent manner, free from any joint where leak-

age might occur and this is made possible because the frame is made of cast steel which has the same coefficient of expansion as sheet steel and is capable of being successfully welded thereto. The sheet metal extension 15 is protected by a cast iron liner 19 inserted therein and having at its inner end a flange 20 for protecting the welded joint between the member 15 and the member 10. A similar liner 21 is arranged on the bottom of extension 15 with a flange 22 extending over the edge of fire brick lining 54.

In the rear of the drum 10 is a radiator 23 spaced from and detachably connected to the drum 10. The radiator is in the form of a segmental drum, partially surrounding the main drum 10. In order to maintain a gas-tight joint between the main drum and the radiator, it is preferable to have only one point of separation between the two units and have the remaining sections permanently joined together by welding. It is also desirable that the parts joining the drum and radiator have rigidity so as to maintain their shape and form and for these and other reasons I have found it advantageous to use two connecting collars 24 and 25 made of steel castings. The collar 24 projects from the radiator 23 and is integrally united thereto by welding at the point 26. Similarly the collar 25 projects from the drum 10 and is welded thereto at the point 27. The two collars telescopically engage each other, one having the flange 28 engaging an annular recess 29 in the other and each being provided with outwardly extending flanges 30 secured together by bolts 31. The cast steel collars are protected throughout their entire length by a cylindrical liner 32 formed preferably of cast iron and having an outwardly extending flange 33 protecting the welded joint 27 between the drum 10 and the collar 25. The liner is secured in position by a set screw 34.

The radiator 23 is formed of sheet steel and consists of a segmental body portion 35 and upper and lower heads 36 and 37 which are welded to the body. The smoke flue 38 and the clean-out flue 39 are formed by sheet steel extensions welded to the body 35. Within the radiator 23 is a baffle or deflector plate 40 arranged in an inclined position to extend from a point closely adjacent the inner wall and near the lower end of the radiator to the top of the radiator near the middle thereof. The baffle 40 is also a curved section so that its opposite edges are adjacent to the outer wall of the drum, thereby causing the gaseous products which pass from the drum 10 into the radiator 23 to be deflected to the opposite sides thereof and downward and then upward through the center of the drum to the escape flue 38. To permit of direct draft when firing the furnace and thereby prevent the products of combustion from escaping into the basement area through the

feed door, there is a damper 41 located in an opening in the baffle which is in alignment with the nipple or collar 24 and flue 38. This damper is hinged at 42 and is weighted so as to automatically close by gravity. In case of a sudden explosion of combustible gases in the drum 10, the damper 41 can automatically swing open and allow the gases to pass directly into and through flue 38, rather than pursue their regular course downward and then upward around baffle 40 with a possibility of blowing open door on clean-out 39 and distributing soot, smoke and ashes in basement area. To open the damper 41 mechanically there is provided a vertical rock shaft 43 having an arm 44 adapted to bear against the damper at a point below its hinge pivots 42. Located on the rock shaft 43 and electrically welded thereto is a flat steel washer 43a which seals the opening in a bearing 45 where rock shaft 43 enters, to prevent the products of combustion from finding their way out into the casting area. The bearing 45 in which the rock shaft is journaled is preferably formed of cast steel in order that it may be welded to the sheet steel radiator and thus make a tight joint. The bearing 45 has a flange 46, the underside of which is welded to the head 36 of the radiator. The top face of the flange has a series of raised rings 47 with annular recesses 48 therebetween into which is fitted a complementary part 49 with a series of rings 50 arranged in the recesses 48. The part 47 is fixed to the rock shaft 43 by a set screw 51 and is provided with a lever 52 for actuating the rock shaft and adjusting the damper. A rod 53 extends from the lever to the front of the furnace and provides a convenient handle for opening the damper before opening the fire door. While the bearing 45 is of cast steel, the cooperating part 47 is preferably of cast iron since it does not require welding. Leakage through the damper operating means is effectively prevented by reason of the large number of bearing surfaces formed by the concentric rings 47 and 50 and by the close contact of the bearing member 45 and the washer 43a.

The refractory lining for the portion of the drum 10 which forms the fire pot may be of any suitable construction as indicated at 54 and may be supported on a ring 21 secured within the drum 10, such ring and supports being removable so as to allow lowering the refractory lining to the bottom of the drum 10 at plate 55 forming a lining for oil burners located in the ash pit and extending inward through the ash pit opening. Where solid fuel is used there is provided a grate 56 of any suitable construction or where gas or oil fuel is used any suitable equipment may be installed in place of this grate.

The drum 10 and radiator 35 are surrounded by sheet metal air jacket 57, which at its

lower end engages a supporting ring 58 attached in the middle and at the back of drum 10 and at the bottom and on each side of cast metal member 55. At the front of the furnace there are two cast metal members 59 and 60, which extend from the base to a point above the fire door. At the upper end of member 59 there is a water tank or pan 61. The lower end of member 60 forms the door frame for the ash door 72. These members 59 and 60 are bolted together at a point directly below the cast steel door frame 17, lower member 60 being bolted to the ash pit section and upper member 59 to the cast steel door frame 17, forming a yieldable connection to allow for the expansion and contraction of the members. The member 60 has a bead 62 extending around the door frame 17 and the bolts 63 which connect the members 62 and 17 pass through this bead. Thus there is a portion of the bolt extending through the hollow of the bead which is sufficiently flexible to compensate for the different expansions in the members 17 and 59 and 60, and also drum 10.

The construction described permits of detaching the drum 10 from radiator 35 for convenience in shipment. When the furnace is assembled, the radiator 35 is coupled to the drum 10 by engaging the collars 24 and 25 with each other, wrapping a piece of pure asbestos rope between the flanges of the two parts and bolting together with the bolts outside of the asbestos rope. The outer sheet metal jacket 57 may then be put in place and secured in the usual manner. The liners 19 and 32 are placed in their respective positions to protect the casing around the fire door opening and the escape flue for the hot gaseous products of combustion.

In operation, the gases both before and after combustion are prevented from passing out into the air jacket either from the drum 10, the radiator 35, or any of the connecting parts. This is because all of the joints which are exposed to such gases have been electrically arc welded, thus forming a gas-tight seal and making the product potentially seamless.

What I claim as my invention is:

- 50 1. In a furnace, a casing formed of adjacent sheet metal and cast metal sections having welded joints therebetween.
- 55 2. In a furnace, the combination with a drum formed of sheet metal, of a door frame formed of cast metal and a welded joint between said door frame and drum.
- 60 3. In a furnace, the combination of a drum formed of sheet metal parts having the joints therebetween welded and one or more cast metal members welded to the said drum to impart rigidity thereto and to form a gas-tight seal.
- 65 4. In a furnace, the combination with a drum formed of sheet steel, a door frame

formed of cast steel and a welded joint between said door frame and said drum.

5. In a furnace, the combination of a drum formed of sheet steel parts having the joints therebetween welded and one or more additional members formed of cast steel welded and unriveted to said drum. 70

6. In a warm air furnace, a sheet steel drum forming the body portion of the furnace and having a door opening therein, a cast steel door frame surrounding said opening and a welded joint between said cast steel door frame and sheet steel drum. 75

7. In a warm air furnace, a body portion formed of sheet steel and having welded joints and a door frame of substantially heavier section than said sheet steel, said door frame forming a reinforcement for imparting rigidity to said sheet steel structure at the door opening and being composed of a steel casting and a welded joint between said cast steel door frame and sheet steel body. 80

8. In a warm air furnace, a body portion formed of sheet steel having a door opening therein, a cast steel door frame having flanges extending transversely to the surface of said body portion, said flanges being welded to said drum forming a gas tight joint and a cast iron lining within said door frame having a flange overlapping the marginal portion of said sheet metal door opening and protecting the said weld from combustion gases within said body portion. 90

In testimony whereof I affix my signature.
